F. N. CATUDAL

LAWN EDGING IMPLEMENT

Filed April 19, 1927

Frederic N. Catudal

By *Clarence O'Brien*
Attorney

UNITED STATES PATENT OFFICE.

FREDERIC N. CATUDAL, OF NEWTON, IOWA.

LAWN-EDGING IMPLEMENT.

Application filed April 19, 1927. Serial No. 184,933.

The present invention relates to an improved gardening tool which is better known in the art as a lawn edging implement, that is, a device which is adapted for trimming the edge of a lawn adjacent the concrete sidewalk for the purpose of making the lawn edge straight and providing a drainage gutter.

Briefly, the improved implement comprises a shaft provided at one end with a suitable handgrip and provided at its opposite end with novel means for adjustable mounting of the removable excavating and trimming device.

One feature of importance is the novel connecting means between the device and said shaft, the same comprising a connecting socket and a notched and laterally off-set shank.

Another feature of the invention is the trimming or edging device which is made in the form of an excavating shoe provided with one straight side and one inclined side to facilitate movement and excavation.

A further feature is an adjustably mounted roller which facilitates the situation of the device and which regulates the depth of the cut.

A further feature is the novel connecting arch between the shoe and the shank.

Other features and advantages of the invention will become apparent from the following description and drawing.

In the accompanying drawing:

Figure 1 is a side view of the complete implement showing the approximate method of use.

Figure 2 is an enlarged end view of the excavating device.

Figure 3 is a side view of the shoe per se.

Referring to the drawings in detail, it will be seen that the reference character 1 designates the shaft which is of any appropriate length and construction. At the upper end of this is a handgrip 2 mounted on a bail 3 which is connected to the shaft through the medium of a socket 4. The socket in this instance forms a cap to fit over the end of the shaft and it is suitably riveted or otherwise fastened in place.

At the opposite end of the shaft is a coupling or attaching device which comprises the socket 5 suitably fastened in place, this socket being formed with an integral shank 6 of square cross section. The shank is bowed longitudinally to off-set it with respect to the

longitudinal axis of the shaft and it is provided in its upper side with notches 7.

The excavating device is made up of two principal parts. First, the shoe 8 comprises a sheet metal body which is formulated to provide a straight wall 9 and an inclined wall 10 extending at an acute angle to the straight wall and being in an upper attaching portion 11 which is disposed in spaced parallelism with the wall 9. The opposite ends of the body are bevelled to provide cutting edges and to render the device reversible. The connecting portion 12 is rounded somewhat to facilitate actuation and sliding of the shoe. The second principal part 13 comprises a single metal casting including an arch, the bight portion 14 of which is comparatively heavy and provided with a square hole through which the shank 6 extends. At this point, a set screw 15 is provided for selective reception in the notches 7. The arms 16 of the casting are disposed in outwardly directing relation and terminate in cross heads 17 which are riveted to the side wall of the shoe. Incidentally the straight wall 9 of the shoe is provided with a vertical row of apertures 18 for selective reception of the axle 19 of a small gauge roller 19. The axle is held in place by retaining nuts 20, arranged on opposite sides of the wall 9 as shown in Figure 2. The elevation of the roller can thereby be changed from time to time to regulate the depth of the cut.

After carefully considering the foregoing detailed description in connection with the accompanying drawing, it is believed that a clear understanding of the construction, method of assembly, and the use of the invention will be had. Also in making an analysis of the structure, it has been particularly noted that the invention is characterized by simplicity and inexpensiveness of manufacture, as well as convenience and compactness in the arrangement of parts. These and other advantages and features of the invention have doubtless been made apparent. Therefore, more lengthy description is thought unnecessary.

While the preferred embodiment of the invention has been shown and described, it is to be understood that minor changes in shape, size and arrangement of parts coming within the scope of the adjoining claims may be resorted to if desired.

I claim:

1. In a structure of the class described, a

shaft, a handgrip fastened to the upper end thereof, a socket fastened to the lower end of the shaft, and equipped with a notched shank, an excavating and trimming shoe, and an attaching device therefor connected thereto and adjustably and slidably mounted upon said shank and provided with a set screw for selective reception in said notches.

2. In a structure of the class described, a shaft, a handgrip carried by the upper end of the shaft, a socket fitted on the lower end of the shaft, a shank carried by said socket, said shank being square in cross section and provided on its top edge with longitudinally

spaced notches, said shank being also bowed longitudinally, a cutting shoe and a device for adjustably mounting said shoe on said shank, said device comprising an arch having a relatively thick bight portion provided with a square hole through and beyond which said shank is adapted to extend, a set screw carried by said bight portion and adapted to be selectively seated in the notches in said shank, the arms of said arch terminating in cross heads fastened to portions of said shoe. 15 20 25

In testimony whereof I affix my signature.

FREDERIC N. CATUDAL.
